UNITED STATES PATENT OFFICE.

ROY RANDOLPH RIEPEN, OF ST. JOSEPH, MISSOURI.

GARAGE-DOOR LATCH.

Application filed April 8, 1926. Serial No. 100,733.

This invention relates to garage door latches and more particularly to a latch for garage doors which are formed of a plurality of panels connected at opposite sides 5 of the door frame so that one panel may be separately swung to provide a door permitting ingress of persons to the garage without the necessity of moving all of the panels.

An important object of the invention is 10 to provide a single latch mechanism which will latch both sets of the panels and which may be employed to release one of the panels without releasing the remaining thereof or for releasing all of the panels, as is desired.

15 A further object of the invention is to produce a device of this character which is readily adjustable to permit its use with doors of varying heights and thicknesses.

20 A still further object of the invention is to provide a door latching mechanism for controlling the door panel including a plurality of bolts and link connections for simultaneously operating these bolts together with a latch mechanism for a second associated panel so constructed that operation 25 of the link mechanism in a predetermined manner will release only the latch while leaving the bolts in their latching position.

These and other objects I attain by the 30 construction shown in the accompanying drawings, wherein for the purpose of illustration is shown a preferred embodiment of my invention and wherein:—

Figure 1 is an inside elevation of a garage 35 door having latch mechanism constructed in accordance with my invention;

Figure 2 is a longitudinal sectional view therethrough on the line 2—2 of Figure 1;

Figure 3 is a longitudinal sectional view 40 through the latch for holding the single panel;

Figure 4 is an end elevation of the latch;

Figure 5 is an enlarged sectional view taken on the line 5—5 of Figure 1;

Figure 6 is a longitudinal sectional view 45 through the connection to the door bolt;

Figure 7 is an end elevation thereof;

Figure 8 is an inside elevation of a two panel garage door embodying a latch constructed in accordance with my invention;

Figure 9 is a similar view of a two panel garage door where the two panels are pivotally connected to one another and only connected to one side of the door casing;

50 Figure 10 is a front elevation of one of the bolt links;

Figure 11 is a side elevation thereof;

Figure 12 is an enlarged rear elevation showing the coaction of the latch mechanism with the link.

60

Referring now to the drawings and more particularly to Figures 1 to 7 thereof, the numeral 10 generally designates a door casing having associated therewith a door formed in two sections 11 and 12, both of 65 which must be opened to permit use of the full width of the door opening. The door section 12 operates as an ordinary door, permitting passage of persons to and from the garage without the necessity of opening 70 both door sections 11 and 12. The door section 11 in Figure 1 is illustrated as formed in two panel sections 11^a and 11^b, of which the panel 11^b meets with the section 12. Upon the inner face of the panel 11 adjacent 75 the panel 12, a latch 13 having a spring-pressed bolt 14 is arranged. The casing 15 of this latch has in its rear face a slot 16 through which projects a pin 17, for a purpose presently to appear.

80 Through the panel 11^b adjacent, and as at present illustrated above the lock 13, the panel is formed with a bore 18 suitably bushed, as at 19, for guidance of a square shaft 20, the outer end of which is provided with a pivoted handle element 21, the free end of which may be swung to engage an eye 22 through which a padlock 23 may be directed for locking the handle against movement. The shaft 20 is made of sufficient 85 length to permit its use with doors of varying thicknesses and is provided with spaced openings for the passage of a retaining pin 24 abutting a washer 25 which, in turn, engages against an oval plate 26 to hold the 90 same against the inner end of the bushing 19. The oval plate 26 has its long axis vertically directed and is provided at each end thereof with a horizontally extending rearwardly directed pin 27 adapted to engage in a slot 28 formed in the end of a link 29. The slot 28 extends longitudinally of the link so that the link is both pivotally and longitudinally shiftably connected with the 95 plate.

100 Secured to the panel 11^b in vertical alignment with the plate 26 are spring latches 30, the bolts 31 of which are adapted to engage in the casing 10 to latch the panel 11^b against movement with relation thereto. Threaded upon the inner ends of these bolts 110 31 are connectors 32 slotted for the reception

of the ends of the links 29. The links 29 are formed in two groups of which 33 indicates the upper links or links for connecting the upper bolt with the plate 26 and 34 the link for connecting the lower bolt with this plate. The links 34 determine the height of the mechanism above described from the floor of the garage and are of fixed length while the links 33 are made of sufficient length to accommodate a garage door of the greatest height in which such doors are made and are provided with a longitudinally extending series of openings 35 adapted to interchangeably receive a retaining pin 36 whereby the upper end of the link is connected to the connector 32. The surplus length of the links 33 may be removed in any suitable manner and the threaded connection 37 of the connector 32 of the bolt 14 provides for regulatory adjustment to compensate for improper spacing of the openings 35.

In the operation of the structure, in so far as it has now been described, when the handle 21 is oscillated, the plate 26 will be rotated and by its rotation will first tend to cause movement of the links 34 in a direction transversely of the door. If the rotation is in the proper direction, the lower link 34 will engage against the pin 17 of the bolt 14 during this transverse movement with the result that the bolt is withdrawn, permitting the door section 12 to be swung to open position. This movement of the bolt is accomplished before sufficient longitudinal movement of the links 33 and 34 takes place to cause the bolts 31 to be withdrawn from the door casing with the result that the door section 11 will remain latched. Continued movement of the handle will, however, cause the bolts 31 to be withdrawn so that both door sections are freed for movement. If the door handle is moved in the opposite direction, it will be noted that the link 34 will move away from the bolt pin 17 and will not engage thereagainst. Therefore, if the handle is partially swung in one direction, it will release the door section 12 for opening movement and the handle may then be swung in the opposite direction and will release the door section 11. By limiting swinging movement of the handle in the first direction so that it may only be rotated in such direction a distance sufficient to cause operation of the lock 14, insurance is provided against accidental release of both door sections when it is desired only to open the door section 12. Such a limiting means is provided by the pin 17 which, by its engagement with the rear end of the slot 16 and with the link 34, will positively limit the swinging movement of the plate.

A second means for preventing such accidental releasing of the door section 11 may

be readily provided by pivoting upon the inner surface of the panel section 11^b at the opposite side thereof from the mechanism just described, a second plate 26' similar to the plate 26 first described and arranging above and below this plate latches 30'. This plate is connected with the latches by links 34' and 33' and the plates 26 and 26' are connected by a link 38 which is made adjustable in the same manner as the links 33. 70 This link has a slot 39 which engages with the lower pin 27 of the plate 26 so that as the lower end of this plate moves toward the plate 26', no movement of the link is effected while, if the lower end of the plate 26 tends to move away from the plate 26', the link 38 causes a similar movement of the plate 26' and accordingly of the bolts 31' of the latches 30'. With a construction of this character, it will be obvious that a 80 movement of the latch handle 21 causing the lower end of the plate 26 to move toward the plate 26' will cause the bolt 14 to be operated, but will be ineffectual to cause any operation of the bolts 31' so that the door section 11 remains latched while the door section 12 is released. To release both door sections, it is, therefore, necessary to first swing the latch handle in one direction to release the door section 12 and then 90 in the opposite direction to release the door section 11. It will be obvious that in a structure such as shown in Figure 8, the operation will be the same as that first described while in a structure, such as shown 100 in Figure 9, where the latch 13 is omitted, the bolts 31 form the sole means for latching the door and may be withdrawn by rotation of the handle in either direction.

Certain other changes being possible in 105 the construction hereinbefore set forth without in any manner departing from the spirit of the invention, I do not limit myself to such specific structure except as herein-after claimed.

I claim:—

1. In combination with a door structure including a frame and two door sections associated therewith and connected with opposite sides of the frame, bolts carried by one of said sections and engaging with the frame at the top and bottom of the section, a rotatable shaft directed through said door section between the bolts, a plate secured to the shaft at the inner face of the door and linked to said bolts, a latch carried by said door section and having a bolt for engagement with the other of the door sections and an operative connection between the bolt of said latch and the link connecting said plate with one of said bolts when the plate is rotated in one direction by the shaft disengaging the bolt of the latch prior to disengagement of the first named bolts from the casing. 110 115 120 125 130

2. In combination with a door structure including a frame and two door sections associated therewith and connected with opposite sides of the frame, bolts carried by one of said sections and engaging with the frame at the top and bottom of the section, a rotatable shaft directed through said door section between the bolts, a plate secured to the shaft at the inner face of the door and linked to said bolts, a latch carried by said door section and having a bolt for engagement with the other of the door sections and an operative connection between the bolt of said latch and the link connecting said plate with one of said bolts when the plate is rotated in one direction by the shaft disengaging the bolt of the latch prior to disengagement of the first named bolts from the casing, said connection between said link and the bolt of said latch positively limiting rotation of the plate in said direction while the bolts coacting with the casing are still in engagement therewith.

3. In combination with a door structure including a frame and two door sections associated therewith and connected with opposite sides of the frame, bolts carried by one of said sections and engaging with the frame at the top and bottom of the section, a rotatable shaft directed through said door section between the bolts, a plate secured to the shaft at the inner face of the door and linked to said bolts, a latch carried by said door section and having a bolt for engagement with the other of the door sections and an operative connection between the bolt of said latch and the link connecting said plate with one of said bolts when the plate is rotated in one direction by the shaft disengaging the bolt of the latch prior to disengagement of the first named bolts from the casing, springs urging the first named bolts outwardly for engagement with the casing, the link connections of the bolts with the plate permitting independent inward movement of the first named bolts toward the plate during closing movements of the door.

4. In combination with a door structure including a frame and two door sections associated therewith and connected with opposite sides of the frame, bolts carried by one of said sections and engaging with the frame at the top and bottom of the section, a rotatable shaft directed through said door section between the bolts, a plate secured to the shaft at the inner face of the door and linked to said bolts, a latch carried by said door section and having a spring-pressed bolt for engagement with the other of the door sections, the latch casing having a slot, a pin projecting through said slot and into the path of movement of one of the links connecting the plate with one of the first named bolts when the plate is rotated in one direction.

5. In combination with a door structure including a frame and two door sections associated therewith and connected with opposite sides of the frame, bolts carried by one of said sections and engaging with the frame at the top and bottom of the section, a rotatable shaft directed through said door section between the bolts, a plate secured to the shaft at the inner face of the door and linked to said bolts, a latch carried by said door section and having a spring-pressed bolt for engagement with the other of the door sections, the latch casing having a slot, a pin projecting through said slot and into the path of movement of one of the links connecting the plate with one of the first named bolts when the plate is rotated in one direction, said pin engaging against the rear end of its slot prior to disengagement of the first named bolts from the frame.

6. In combination with a door structure including a frame and two door sections associated therewith and connected with opposite sides of the frame, bolts carried by one of said sections and engaging with the frame at the top and bottom of the section, a rotatable shaft directed through said door section between the bolts, a plate secured to the shaft at the inner face of the door and linked to said bolts, a latch carried by said door section and having a bolt for engagement with the other of the door sections and an operative connection between the bolt of said latch and the link connecting said plate with one of said bolts when the plate is rotated in one direction by the shaft disengaging the bolt of the latch prior to disengagement of the first named bolts from the casing, a second plate pivoted to the door section in spaced relation to the first named plate, a connection between said plates whereby the plates move in unison when the handle is rotated in one direction and the first named plate moves alone when the handle is rotated in the opposite direction, the other casing engaging bolts carried by the first named section of the door and connected with the last named plate to be operated thereby.

7. In combination with a door structure, a pair of spring-pressed casing engaging bolts arranged at opposite ends thereof, a plate rotatably mounted upon the door structure intermediate the bolts, links connecting said bolts and said plate, each having at their plate engaging end a longitudinally extending slot, pins carried by the plate for engagement in the slots, one of said links being fixed as to length, the other of said links having in its bolt engaging end a series of longitudinally spaced openings and a coupling between the free end of the last named link and the bolt including a member having an opening for the passage of a pin adapted to engage in one of the open-

ings of the link, said member being adjustably threaded in its engagement with the bolt.

8. In combination with a door structure, a pair of spring-pressed casing engaging bolts arranged at opposite ends thereof, a plate rotatably mounted upon the door structure intermediate the bolts, links connecting said bolts and said plate, each having at their plate engaging end a longitudinally extending slot, pins carried by the plate for engagement in the slots, one of said links being fixed as to length, the other of said links having in its bolt engaging end 15 a series of longitudinally spaced openings,

a coupling between the free end of the last named link and the bolt including a member having an opening for the passage of a pin adapted to engage in one of the openings of the link, said member being adjustably threaded in its engagement with the bolt and means for operating said plate including a shaft directed through the door, a handle member pivoted to the outer end of the shaft, the door having attached thereto an eye, the handle having in its free end a slot through which the eye may extend. 20 25

In testimony whereof I hereunto affix my signature.

ROY RANDOLPH RIEPEN.
